UNITED STATES PATENT OFFICE.

FRIEDRICH WANZ AND FRANZ WANZ, OF VIENNA, AUSTRIA-HUNGARY.

INHALING APPARATUS.

SPECIFICATION forming part of Letters Patent No. 629,883, dated August 1, 1899.

Application filed March 4, 1898. Serial No. 672,598. (No model.)

To all whom it may concern:

Be it known that we, FRIEDRICH WANZ and FRANZ WANZ, citizens of Austria, residing at I. Graben 29, Vienna, in the Empire of Austria-Hungary, have invented a certain new and useful Improved Mask or Inhaling Apparatus for Use in Noxious Atmospheres, of which the following is a specification.

This invention relates to an improved mask or inhaling apparatus for the use of persons whose vocation entails lengthened confinement in apartments or localities wherein the atmosphere is charged with noxious gases, the present apparatus being devised after many trials with existing contrivances.

An inhaler or respirator constructed according to our invention comprises a breathing mask or vizor which may be fitted tightly onto the wearer's head by means of a pneumatic or padded ring in conjunction with a covering-ring of india-rubber, so as to entirely cover the face and keep out the injurious gases, while the nose and mouth are left free for ordinary breathing. It also comprises means for controlling respiration, the same consisting of a gas-tight pouch containing potash in a solid state and of a chamber containing compressed oxygen.

The essential characteristic of the invention is that owing to the employment of solid dry caustic potash the interior of the face guard or mask is effectually cooled and perspiration or the development of vapor prevented, the reagent (without the addition of any absorbing media or intermediate agents) offering an extended surface which greedily attracts and combines with the carbonic acid and moisture of the air exhaled by the wearer. By these means the temperature of the interior of the mask is reduced, with the result that the glass of the sight-aperture is never dimmed, while at the same time the mask admits of natural breathing through the nose, the nose-spring and smoke-glasses hitherto considered indispensable in instruments of this class being omitted from the present construction.

The construction of the said apparatus is shown on the accompanying drawings in which—

Figure 1 shows a perspective view of the ap-

paratus, and Fig. 2 a cross-section of the same. Fig. 3 shows in a greater measure a vertical cut through the bag for the reception of the absorbing medium and through the tubes 55 which enter into the same. The valves in the tubes Nos. 10 and 11 are marked 17 and 18.

The mask 1 has in front a glass window 2, on the inner side of which is a wiper 3, that can be turned around on the glass by means 60 of an external button 4 like the pointer of a dial, in order to clear the glass of condensed moisture from the breath. The edge of the mask 1 is lined with a cushion 5, which either consists of a caoutchouc covering filled with 65 wadding or other soft material or it is made of an inflated flexible tube. This cushion serves to inclose the face of the wearer in an air-tight manner. The air-tight joint is further insured by a caoutchouc conical part 17', 70 covering the cushion 5 and having a central opening, which conical part is arranged so as to press at its base tightly against the face of the wearer when the mask is fitted on.

To the mask is attached a hood 6, made of 75 gas-tight material, which is made double all around the lower part, so as to form a closed chamber, as shown at 7 and 9. In this chamber may be provided in front a partition 9 (shown dotted at Fig. 1) for a purpose to be 80 presently described. The hollow chamber of the hood has smooth inside surfaces, it being unnecessary to provide a large extent of surface for the purifying or absorbing medium.

From the mask 1 project at the front part 85 7 of the hood two tubes 10 and 11, which are provided with valves opening in contrary directions, so as to serve as inlet and outlet for the air-supply to the wearer. At a suitable part of the hood a tube 12 enters, the other 90 end of which is connected to a receptacle 13, preferably separate from the other part of the apparatus and which contains compressed oxygen. The valve 14 serves for regulating the discharge of oxygen into the tube 12. On 95 the mask 1 are also provided straps or, preferably, elastic bands 15 for passing around the head in order to insure the close fit of the mask to the face.

In the front part 7 of the hood, and, if necessary, also in other parts, is placed caustic potash in sticks or lumps. For enabling this

to be introduced the hood has an opening which is closed by bars 16, that are made to nip the sides together by means of screws.

When required to be used, the hood is turned up at the back, so as to expose the cushion 5. The mask 1 is then applied to the face and is secured to the head by the bands 15, after which the hood is turned down over the head. The exhaled carbonic acid passes into the front part 7 of the chamber, where the caustic potash is situated, which greedily takes up and combines with the carbonic acid and the moisture, and thereby also reduces the temperature.

15 In order to prevent the possibility of again inhaling any not-absorbed carbonic acid, the partition 9 may be provided for causing the carbonic acid to travel a longer distance, as indicated by the arrows, it being made after 20 coming in contact with the caustic potash—say on the left-hand side of the partition—to pass thence in a backward direction (to 8) and from the back forward again on the other side, where it is again brought in contact with caustic alkali at 7 and other places, if necessary. The oxygen coming from the vessel 13 mixes with the uncondensed nitrogen in the chamber 7 8 and passes thence through the inhaling-tube 11 into the mask.

30 Having thus described the nature of this invention and the best means we know of carrying the same into practical effect, we claim—

1. In an inhaling apparatus, the combination with a mask 1, a soft cushion 5, surrounding the edge thereof, an annular conical part 35 17' covering said cushion and adapted to fit at its base tight against the face, elastic bands

or straps for securing the mask on the head, a hood attached to said mask, having a closed chamber 7, 8, at bottom, which contains material for absorbing carbonic acid and moisture, inhaling and exhaling tubes provided with valves connecting the mask with said chamber, and means for supplying fresh air or oxygen in regulated quantity to the said chamber 7, 8, of the hood, substantially as described.

2. An inhaling apparatus wherein the mask of the hood 6 is provided with a closing-cushion 5 and closing annular part 17' fitting close against the face for effectually cutting off the noxious gases from the respiratory organs, in combination with the hollow annular chamber 7, 8 with smooth inner surface into which open first the tubes 10, 11, that pass directly to the mask in front of the respiratory organs, and are provided with suitable inlet and outlet valves, and secondly an air or oxygen supply pipe 12, the chamber 7, 8, being charged with solid caustic potash, or other suitable solid substance for combining with carbonic acid, and absorbing moisture and heat, such substance being situated in the immediate neighborhood of the entering gas and aqueous vapor so as to act effectually thereon without requiring to be spread over extended surfaces, substantially as described.

In testimony whereof we have hereunto set our hands in presence of two subscribing witnesses.

FRIEDRICH WANZ.
FRANZ WANZ.
